UNITED STATES PATENT OFFICE.

EMMERY H. FAHRNEY, OF CHICAGO, ILLINOIS.

DESIGN FOR A BASE AND CYLINDER FOR INTERNAL-COMBUSTION ENGINES.

SPECIFICATION forming part of Design No. 34,177, dated March 5, 1901.

Application filed September 10, 1900. Serial No. 29,607. Term of patent 7 years.

To all whom it may concern:

Be it known that I, EMMERY H. FAHRNEY, a citizen of the United States, residing at Chicago, in the county of Cook and State of Illinois, have invented a certain new and original Design for a Base and Cylinder of an Internal-Combustion Engine, for which the following, in connection with the accompanying drawings, is a full, clear, and exact specification.

In the said drawings, Figure 1 is a perspective view of a base and cylinder of an internal-combustion engine embodying my design. Fig. 2 is a transverse section thereof, taken on the line 2 2, Fig. 3; and Fig. 3 is a longitudinal vertical section taken on the line 3 3, Fig. 2.

The leading features of my design are the rectangular cylinder-casting A and base J.

The cylinder-casting A is rectangular in appearance in both plan view and side elevation, and it is higher vertically than it is wide when looking at it from the end, and in plan view it presents an oblong, in which appear two cylindrical cavities B C, extending outwardly, from each of which is an elongated channel D, in whose outer ends are formed counterbores E. In the broad side of the cylinder-casting A appears the rectangular opening F, and crossing this opening in a vertical direction appear two cylindrical bodies G H, below which, at the lower edge of said broad

side, are two bosses I, spaced a short distance apart.

The cylinder-casting A appears on the top of a base J, whose sides flare outwardly and downwardly from the broad sides of the cylinder-casting A and terminate in horizontal flanges K, extending lengthwise of said broad sides, and in the broad side of the base J appear an oblong opening L, and within the base, just above each of two cylindrical end openings M, appears a lug N, which project from the inner end walls of the base toward each other, and extending downwardly from the top of the base on one side and near each end is a lug O, while at the upper corner of the opening L is an inwardly-projecting lug P, and diametrically opposite said lug P, on the opposite broad side wall of the base J, is a similar lug P'.

In the bottom of the base J are two countersinks Q.

Having thus described my invention, what I claim as new therein, and desire to secure by Letters Patent, is—

The design for a base and cylinder of an internal-combustion engine substantially as herein shown and described.

EMMERY H. FAHRNEY.
